UNITED STATES PATENT OFFICE.

FRANK S. INGOLDSBY AND JOSEPH R. BOWLING, OF ST. LOUIS, MISSOURI, ASSIGNORS TO THE INGOLDSBY AUTOMATIC CAR COMPANY, OF ST. LOUIS, MISSOURI, A CORPORATION OF WEST VIRGINIA.

DOOR FOR RAILWAY-CARS.

SPECIFICATION forming part of Letters Patent No. 788,646, dated May 2, 1905.

Original application filed February 2, 1903, Serial No. 141,415. Divided and this application filed November 21, 1903, Serial No. 182,064.

To all whom it may concern:

Be it known that we, FRANK S. INGOLDSBY and JOSEPH R. BOWLING, citizens of the United States, residing at St. Louis, in the State of Missouri, have invented a certain new and useful Improvement in Doors for Railway-Cars, of which the following is a full, clear, and exact description, reference being had to the accompanying drawings.

10 The invention relates to certain improvements in doors for railway-cars, particularly such as are constructed of metal, the features which are peculiar to the invention being clearly described herein and being definitely 15 set out in their essential combinations in the claims, to which reference is hereby made for a summary of the invention.

In the drawings, Figure 1 is a side elevation 20 of a portion of the outside of a car, showing how our doors are applied thereto. Fig. 2 is a longitudinal sectional view of a portion of a car, showing our doors as they appear when viewed from the inside of the car. Fig. 3 is a transverse section of so much of the car as 25 is necessary to show our doors applied thereto. Fig. 4 is a detail in side elevation at one of the lower corners of the upper side door, showing the gravity-latch. Fig. 5 is a vertical cross-section of Fig. 4. Fig. 6 is a side 30 elevation of the latch itself, being taken from the same point of view as Fig. 4, omitting intermediate members.

The side of the car is designated A. The side is composed generally of two portions—a lower 35 plate a^6 , terminating in an angle-strip a'' , and an upper portion composed of slats a^7 . At the upper edge of the slatted portion is a chord consisting of a pair of oppositely-facing angle-beams a^8 , riveted back to back through their 40 vertical sides. At the bottom of the side is a lower chord, itself a plate-girder, composed of the plate a^9 and upper and lower flanges a^4 a^5 therefor. The plate a^9 of this girder stands outside of and continues downward from the 45 plate a^6 .

D designates a cross-beam riveted at its ends

to the plate-girder and braced by strengthening angle-irons d' .

F designates the ridge-plate of the car, made in two sections resting on and secured to the 50 cross-beam D. The construction and support of the ridge-plate are shown, described, and claimed partly in our prior application, Serial No. 120,922, filed August 25, 1902, and partly in the application of Frank S. Ingoldsby, Serial No. 120,959, filed August 25, 1902.

Pivoted to the ridge-plate are dumping-doors, as G, provided with floor-beams g , which are adapted to be engaged by hooks K, pivoted to the sides of the car and projecting 60 through the lower flange a^5 thereof, these hooks being connected by a link L for operating the same.

The car is provided at each end with an inclined floor C, as shown in Fig. 3. In the side 65 of the car is provided a doorway, across the upper portion of which extends a plate a^{18} .

The structure of the car-body proper, including the sides, dumping-doors, and inclined floor, does not form any part of the invention 70 covered by this application, the same being embraced in application, Serial No. 141,415, filed February 2, 1903, of which this is a division.

The doorway through the car side is adapted 75 to have its lower portion closed by the door T, which is hinged at the lower edge of the doorway. This door may thus be turned down into a horizontal position, as shown in full lines in Fig. 3, forming a platform upon which the load may be wheeled by a wheelbarrow in filling the car, or it may be turned up vertically to close the doorway, as shown in dotted lines in that figure. On the under side of this door it is provided with steps t to enable the 85 attendant to more easily climb out of the car.

The upper portion of the doorway above the door T and below the plate a^{18} of the car side is adapted to be closed by a small sliding door U, which carries at its upper end rollers 90 u^6 , whereby the door may be slid along and suspended from a track a^{13} , carried by the

outer side of the car side. When in position, the lower edge of this door is swung into the doorway, thus not only closing the doorway, but holding itself from longitudinal shifting. 5 This is shown, described, and claimed in our application, Serial No. 120,923, filed August 25, 1902.

In order to provide a simple and efficient latch for locking the two doors which close 10 the doorway in place, we have provided the mechanism shown more clearly in Figs. 4, 5, and 6. Pivoted to a stud v , secured to the transverse flange a^4 of each of the vertical posts a^2 at the doorway, is a gravity-latch V , 15 so proportioned that if it be turned up into the position shown in dotted lines in Fig. 5 gravity will tend to hold it, whereas it may be swung downward by a slight force into the position shown in full lines in that figure. 20 When the latch V is turned up into the position shown in dotted lines, it is out of the way of the door T . When the latter has been turned up into vertical position, however, and the latch swung downward into its lowermost 25 position, its nose v' passes into an opening a^5 in the flange a^4 and, standing in front of the door T , effectively prevents it from being turned down. Now when the small upper door U is swung inward its lower end u lies 30 across a projecting boss v^2 on the side of the latch V , so that the door U locks this latch in its downturned position, thereby effectively locking the door T . The door U carries a 35 pair of sliding bolts u' , connected by a link u^2 to an operating-handle u^3 . When this operating-handle is drawn outward, the bolts are drawn toward each other, and when the operating-handle is forced inward the bolts are spread outward. In this outward spreading 40 the bolts pass between the outer flange of the post a^2 and the edge of the latch V , and thus hold the upper door in place against either inward or outward movement. A seal- 45 pin u^4 through the operating-handle u^3 and a stationary clip holds the bolts in place. It will thus be seen that an effective lock is provided. The lower doors are locked by the 50 latches V . The latches are locked by the upper door U . The upper door is locked by the bolts u' , and these bolts are locked by the seal-pin. The gravity-latch V is so proportioned that when it is turned into the uppermost position gravity will normally hold it there; but a slight jerk to the car will throw 55 it downward. Thus if the attendant turns down simply one latch after he has turned up the door T the probability is that the other will be automatically thrown down in some movement given to the car before the upper door is locked in place.

Having described our invention, we claim—

1. In a car, the combination of a side provided with a doorway, a door hinged to the lower portion of said doorway and adapted to 65 be swung into a substantially vertical or closed

position, a door-post having a face at right angles to said side and provided with an opening, and a gravity-latch pivoted to said face above the upper edge of said door to swing at right angles to said face and so positioned as 70 to be swung down to engage the edge portion of the door when the latter is closed, said latch being provided with a nose adapted to take into the opening in the post.

2. In a car, the combination of a side having 75 a doorway therein, a door hinged to the lower portion of said doorway and adapted to be swung up into a substantially vertical or closed position, a post on the side of said doorway, a gravity-latch pivoted to the said post 80 at a point above the upper edge of said door and swinging in a plane at right angles to the plane of movement of the door to engage the upper edge portion of the same when closed, said latch being provided with a laterally-projecting boss, and an upper door for said doorway pivoted on the upper portion of the same and adapted to be swung downwardly to close the upper portion of the doorway and to laterally 85 engage the boss of said latch. 90

3. In a car, the combination of a side having 95 a doorway therein, a door hinged to the lower portion of said doorway and adapted to be swung up into a substantially vertical or closed position, a post on the side of said doorway, a gravity-latch pivoted to said post at a point above the upper edge of said door and swinging in a plane at right angles to the plane of movement of the door to engage the upper edge portion of the same when closed, 100 said latch being provided with a laterally-projecting boss, an upper door for said doorway pivoted to the upper portion of the same and adapted to be swung downwardly to close the upper portion of the doorway and to laterally 105 engage the boss of said latch, and means for locking the upper door in such position.

4. In a car, the combination of a side having 110 a doorway therein, angular door-posts on opposite sides of said doorway, a door pivoted to the lower edge of said doorway and adapted to be swung up to close a portion of the same, a gravity-latch pivoted to the lateral face of one of said door-posts and positioned to be turned down to engage the free edge of 115 the said door, a second door pivoted to the upper edge of the doorway and adapted to be swung down to close another portion of the same with its lateral edge engaging said downturned latch, and bolts for locking said upper 120 door closed, said bolts passing between the latch and the front flange of the door-post.

5. In a car, the combination of a side provided with a doorway, a post at the side of said doorway, said post having a flange parallel 125 with the side of the car and projecting into the doorway, and a flange at right angles thereto, a door hinged to the lower portion of said doorway and adapted to be swung into closed position with its upper edge adjacent to the first- 130

mentioned flange of the post, and a latch pivoted to the other flange of the post above the edge of the closed door and positioned to engage the upper portion of said door to retain 5 the same between itself and said first-mentioned flange.

6. In a car, the combination of a side having a doorway through it, posts for said doorway having each a face at right angles to the 10 side, a door pivoted to the lower portion of said doorway and adapted to be swung up into closed position therein, a stud on the face of said post which is at right angles to said side, said stud projecting from said face of said post 15 and being a short distance above the upper edge of the closed door, a gravity-latch pivoted to the outer portion of said stud to swing at right angles to said face and engage the upper edge of the closed door or be turned up 20 with the free end resting against said face above said stud.

7. In a car, the combination of a side having a doorway therein, posts for said doorway, a lower door for said doorway, a pivot member carried by one of said posts a short distance above the edge of said door when closed, 25 a latch pivoted to said member and in its down-turned position engaging the edge of said door, said latch being provided with a nose taking in an opening in said post below said pivoted member.

8. In a car, the combination of a side having a doorway therein, a door hinged to the

lower edge of said doorway and adapted to be swung up to close a portion of said doorway, 35 means pivoted to the side of the doorway for engaging the upper edge of said door when closed, a door for closing the upper portion of the doorway, said door when closed engaging such lower-door-engaging means with a 40 vertical edge.

9. In a car, the combination of a side having a doorway therein, a door-post at the side of said doorway, said post having a flange at right angles to the side and a flange parallel to 45 said side and projecting into the doorway, a door hinged to the lower edge of said doorway and adapted to be swung up to close a portion of the same with its upper edge in proximity to the flange projecting into the 50 doorway, a latch pivoted to the other flange of said post above the edge of the closed door in position to be swung down to engage such edge, another door for closing the remaining portion of said doorway, said door having a 55 vertical edge engaging said latch, and a bolt for said last-mentioned door passing between said latch and the flange of the post which projects into the doorway.

In testimony whereof we hereunto affix our 60 signatures in the presence of two witnesses.
